UNITED STATES PATENT OFFICE.

SIMON OPPENHEIMER, OF NEW YORK, N. Y.

DESIGN FOR A VEIL.

SPECIFICATION forming part of Design No. 22,043, dated December 6, 1892.

Application filed November 8, 1892. Serial No. 451,388. Term of patent 3½ years.

To all whom it may concern:

Be it known that I, SIMON OPPENHEIMER, of New York, in the county of New York and State of New York, have invented and produced a new and original Design for Veils; and I do hereby declare the following to be a full, clear, and exact description of said invention, reference being had to the accompanying drawing, and to the letters of reference 10 marked thereon, which forms a part of this specification.

In the drawing the figure represents a lady's veil having my border design.

The leading feature of the design consists 15 in an outer double festooned line of spots and an inner double parallel line of spots. The outer double festooned line is indicated at a and the inner parallel lines at b b. Within the semicircle formed by each of the inner curved lines, which together form a festooned 20 line, is a group of spots c.

What I claim is—

The design for ladies' veils, substantially as shown and described.

In testimony whereof I affix my signature in 25 presence of two subscribing witnesses.

SIMON OPPENHEIMER.
